UNITED STATES PATENT OFFICE.

ALLEN HEETER AND WILLIAM G. MATTERN, OF PORTSMOUTH, OHIO, ASSIGNEES TO THE VULCAN LAST COMPANY, OF PORTSMOUTH, OHIO, A CORPORATION OF OHIO.

GOLF CLUB.

Application filed May 23, 1927. Serial No. 193,669.

Our invention relates to golf clubs.

It is the object of our invention to provide a poured lead insert weight for a golf club, which, when poured, will be interlocking with the golf club, and will not become loosened therein.

It is the object of our invention to provide an insert of lead in a wooden golf club head so arranged that no attaching means is necessary.

It is a further object to provide an attaching means over the poured lead insert of such a character that the insert becomes a strengthening member as well as a weighting member for the golf club.

Referring to the drawings:

Figure 1 is an elevation of the golf club head with the lead insert in position;

Figure 2 is a section on the line 2—2 of Figure 1;

Figure 3 is an elevation of the golf club head with the cavities for the reception of the lead shown ready to receive it;

Figure 4 is a side elevation of the pouring ladle pouring the lead into the cavities in the golf club head, the golf club head being shown in section to illustrate the form of the cavities;

Figure 5 is a plan view showing the lead insert after it has been molded.

Referring to the drawings in detail, 1 is a golf club head of any desired form or size in one side of which there has been bored a pair of inwardly converging, diagonally disposed, screw threaded cavities 2 and 3. The outer ends of these cavities are enlarged to form chambers 4 and 5, which chambers have their axes in line with the screw threaded portions 2 and 3 so that the respective chambers 4 and 5 are tilted at an angle with respect to one another. Each of these chambers is provided with an outwardly extending ears 6 and 7 while they are connected together by a narrow flat bridge 8, which is relatively deep in the direction of the movement of the club when striking the ball.

Thus, when lead is poured into these cavities in the golf club head, there will be provided a pair of screw threaded, inwardly converging members, which will engage that portion of the wooden head designated 9 between them.

This serves to grip the lead weight in the

wooden head so that it cannot become loosened. The screw threaded lead fingers thus formed are designated 10 and 11 and have on their heads the enlarged cylindrical weights 12 and 13 which are provided with extending ears 14 and 15 and are connected together by the semi-circular and relatively narrow and deep bridge 16. The insert has the screw threaded interlocking members, the weighted heads and the connecting bridge so that a truss-like structure is formed that will be retained permanently in position without movement in the head. The lead is poured into the wooden form in molten condition and therefore each insert adapted itself to the irregularities of the cutaway portions of the head with the result that no difficulties are experienced in trying to fit predetermined sizes of cavities and predetermined sizes of lead inserts one to the other, which is a disadvantage of the premolded lead insert, which must be placed in position and attached by some means.

The ladle for pouring the lead is diagrammatically illustrated and numbered 17. The stream of molten metal 18 is poured into the wooden form and allowed to cool and therefore becomes an integral part of the club head.

It will be understood that we desire to comprehend within our invention such modifications as may be necessary to adapt it to varying conditions and uses.

Having thus fully described our invention, what we claim as new and desire to secure by Letters Patent, is:

1. In a golf club, a wooden head having converging cavities and a narrow communicating passageway between said cavities below the surface of the head, and a weighted member inserted therein in molten condition whereby it is interlocked therein.

2. In a golf club head having converging screw threaded cavities and a narrow cutaway portion communicating with said cavities and a poured metal insert applied in plastic condition to said cavities whereby when said insert solidifies a metal insert is interlocked in said wooden golf club head.

3. In a golf club, a wooden head and a molded metal insert consisting of inwardly converging metallic screw threaded members and a narrow bridge connecting said members.

4. In a golf club, a wooden head and a molded metal insert consisting of inwardly converging metallic screw threaded members and a bridge connecting said members, enlarged heads on said screw threaded members of greater diameter than said bridge.
5. In a golf club, a wooden head and a molded metal insert consisting of inwardly converging metallic screw threaded members and a bridge connecting said members, enlarged heads on said screw threaded members of greater diameter than said bridge, and ears projecting beyond said enlarged heads.
6. In a golf club, a wooden head and a molded metal insert consisting of inwardly converging metallic screw threaded members and a bridge connecting said members, enlarged heads on said screw threaded members of greater diameter than said bridge,

and ears projecting beyond said enlarged heads in line with said bridge.

7. In a golf club head, a head, an integral metallic insert melted in said head consisting of inwardly projecting interlocking members for engaging a portion of the head therebetween, a connecting relatively narrow and deep bridge member.

8. In a golf club head, a head, an integral metallic insert melted in said head consisting of inwardly projecting interlocking members for engaging a portion of the head therebetween, a connecting relatively narrow and deep bridge member, and laterally extending heads over the respective interlocking members.

In testimony whereof, we affix our signatures.

ALLEN HEETER.
WILLIAM G. MATTERN.
